UNITED STATES PATENT OFFICE.

JOHN T. HAWKINS, OF TAUNTON, MASSACHUSETTS.

BUFFER-SPRING FOR PRINTING-PRESSES.

SPECIFICATION forming part of Letters Patent No. 313,205, dated March 3, 1885.

Application filed December 26, 1883. (No model.)

To all whom it may concern:

Be it known that I, JOHN T. HAWKINS, of Taunton, in the county of Bristol and State of Massachusetts, have invented a new and useful Improvement in Buffer-Springs for Printing-Presses, which improvement or invention is fully set forth and illustrated in the following specification and accompanying drawings.

The object of this invention is to provide simple and convenient mechanism for operating air-springs whose reactive effort during expansion shall be particularly utilized to a degree equal to the resistance encountered during their compression.

15 The invention consists of the parts or combinations of parts set forth in the claims.

In the accompanying drawings, Figure 1 is a longitudinal vertical section through the center of such parts of a printing-press as are required to illustrate the invention for one end of the press. Fig. 2 is a transverse vertical section at the line X X, Fig. 1, looking to the left, with certain parts omitted not necessary to this figure. Fig. 3 is a vertical longitudinal view, 25 partially in section, of the apparatus complete for both ends of the machine, with the type-bed and roller-ways omitted. Fig. 4 is a view in plan of the means of operating the escape-valve when it is required to throw the springs out of action to enable the operator to turn the machine over the points of reversal without resistance of the springs.

In said figures, the letter A indicates a part of the main frames of the machine; B, an end 35 cross girt or frame, to which the principal parts of the spring apparatus are attached; B', a central cross girt or stay, generally situated immediately under the impression-cylinder, to receive and resist the force of the impression. 40 From B' are extended two brackets, B', to which are pivoted two levers, b, formed upon their upper ends into well-known hook forms to gradually receive without jar the contact of a roller, R, carried in a bracket, R', secured to the 45 under side of the type-bed T. The two levers b are connected by a rod, b', pivoted to each, the central part of said rod being supported upon a roller, r, upon the cross-stay B'.

In the center and upon the right-hand half 50 of the rod b' is formed a yoke, b', within which the left-hand part of the rod b' slides for a short

distance, the end of the left-hand half of rod b' within the yoke b' having a nut, b³, upon it to prevent its withdrawal from yoke b'. Two air-chambers, C C, are secured to cross-stays 55 B. Two plungers, C' C', have a good but easy fit in the chambers C C. The plungers C' C' are made considerably longer in proportion to their respective diameters than is usual in such structures for other purposes. The plungers C' C' are connected to the levers b by the connecting-rods c, said rods being respectively pivoted to both the plungers C' and levers b, as shown.

In the bottom of each plunger C' is a small 65 slack-valve, V, opening into each air-chamber C.

The piston P is made air-tight by the usual leather packing, or may be made a sufficiently tight fit in the chamber C to be air-tight.

To the piston P is secured a screw, P', having a stop, P², upon its outer end to limit the maximum compression to be obtained or minimum volume of air-chamber.

P³ is a hand-wheel secured to a flanged nut, 75 P⁴, working within a guide, P⁵.

S is a stop for limiting the motion of the lever b in one direction.

K K are cocks communicating with the air-chambers C at the respective inward limits of 80 the strokes of the plungers C', as at K'.

K² is a bell-crank lever attached to the plug of one cock K, and K³ a straight lever secured to the plug of the other cock K.

K⁴ is a rod connecting with the two levers 85 K² and K³, and K⁵ is a rod terminating in a handle, K⁶, connected to the other arm of the bell-crank lever K².

I have found, experimentally, that if the plungers C' be made of considerable length in 90 proportion to their diameters, and have each a fair running fit in the chambers C for all pressures required in the chamber of an air-spring, they will be practically air-tight, particularly when slightly lubricated. This is 95 particularly true of such springs as used in a printing-press or in similar machines, from the fact that the time within which the compression and expansion of the air is effected is exceedingly small, affording, even in case of a 100 slight leak of air past the plungers C' under the high pressures, an exceedingly small chance

for a material diminution of pressure from such leakage. To provide, however, that such small loss of air may be restored to the chamber after each compression, a valve, V, is fitted 5 in each plunger C', allowing, upon the withdrawal of either plunger, such escaped quantity of air to re-enter the chamber and establish equilibrium of pressures within and without before the next compression occurs. The 10 roller R alternately engages the hooked ends of the levers b to alternately compress the air confined in the chambers C between the pistons P and the bottoms of the plungers C'. The function of the rod b' is to cause either one of 15 the levers b to withdraw the other, and with it its connected plunger C', to the proper point to properly receive the roller R, as limited by the stop S, in case of slight leakage of air past the plungers C'. Said plungers from this cause 20 (and from slight cooling of the air in the chamber due to radiation of the heat of compression from its surface) are not restored to that position by the expansive action of the air. The lost motion of the nut b³ within the yoke b² is 25 therefore made something less than the whole movement, respectively, of the levers b at the points of attachment of the rod b'.

To vary the accumulations of pressure in the chambers C, the pistons P are moved to or 30 from the bottoms of the plungers C' by means of the hand-wheels P³ and screws P', so as to vary the volumes of the chambers C, and thus increase or diminish at will the maximum pressures obtained. The pistons P being self- 35 packing and air-tight, no air will escape past them; but if a slight leakage past them should occur during compression it will be restored

by the valves V in the same manner as in case of leakage past the plungers C'. The cocks K, as operated by the levers K², K³, K⁴, and K⁵ 40 and handle K⁶, allow the air to escape from beneath the plungers C' whenever the press may be required to be turned over the points of reversal by hand or run without springs, the handle K⁶ being placed for such purpose with- 45 in easy reach of the feeder or attendant.

I do not confine myself to the exact construction of the several parts herein described, as the whole may be varied to suit the proportions and constructions of the various types of 50 printing-presses to which the general principles above described are applicable.

Having thus fully described my said improvements as of my invention, I claim—

1. In an air-spring apparatus, in combination with a pair of air chambers or cylinders and plungers for compressing the air therein, a yoked rod connected to said plungers by vibrating arms or levers, in the manner substantially as described, whereby the same are 55 operated, substantially as and for the purposes set forth.

2. In an air-spring apparatus, an air chamber or cylinder having an adjustable bottom consisting of a piston, as P, provided with a 60 threaded rod passing through a rotary nut fixed in a circular guide, whereby said piston is moved in a right line by the revolution of said nut, substantially as and for the purposes set forth.

JOHN T. HAWKINS.
